UNITED STATES PATENT OFFICE.

AUGUST R. LASSEL, OF WASHINGTON, DISTRICT OF COLUMBIA.

AEROPLANE.

1,016,020.

Specification of Letters Patent.

Patented Jan. 30, 1912.

Application filed November 11, 1909. Serial No. 527,544.

To all whom it may concern:

Be it known that I, AUGUST R. LASSEL, subject of the Czar of Russia, residing at Washington, in the District of Columbia, 5 have invented certain new and useful Improvements in Aeroplanes, of which the following is a specification.

The present invention relates in general to aerial navigation, and more particularly 10 to an airship of the heavier than air type, such as are commonly called aeroplanes.

The object of the invention is the provision of a comparatively simple, light, and rigid construction of aeroplane which embodies 15 novel features of construction for producing and maintaining equilibrium and for directing the movements of the machine while in flight.

The invention further contemplates an 20 aeroplane which will be completely under the control of the operator at all times, the stabilizing and guiding elements being controlled by a single lever which is mounted to swing about a universal joint.

25 With these and other objects in view, the invention consists in certain novel combinations and arrangements of the parts as will more fully appear as the description proceeds, the novel features thereof being 30 pointed out in the appended claims.

For a full understanding of the invention, reference is to be had to the following description and accompanying drawings in which:

35 Figure 1 is a side elevation of an aeroplane constructed in accordance with the invention. Fig. 2 is a front view of the same, portions being broken away. Fig. 3 is a top plan view of the aeroplane, portions being broken away and shown in section. Fig. 4 is an enlarged side elevation of the main operating lever, portions being shown in section. Fig. 5 is an enlarged detail view of the rear wheel and the shock 40 absorbing mechanism employed in connection with the same, portions being shown in section. Fig. 6 is a sectional view on the line 6—6 of Fig. 4. Fig. 7 is a detail perspective view of the outer end of one of the main 45 planes, the auxiliary plane being shown in an operative position, and Fig. 8 is a similar view with the auxiliary plane in an inoperative position.

Corresponding and like parts are referred 50 to in the following description and indi-

cated in all the views of the drawings by the same reference characters.

Specifically describing the aeroplane illustrated on the drawings, the main frame thereof comprises a substantially vertical mast 1 having a skeleton frame 2 at the upper end thereof, the said skeleton frame constituting the body portion of the aeroplane and being covered with a fabric 3 so as to reduce the resistance thereof to the air. 60 The engine 4 and the seat 5 of the operator are arranged within the skeleton frame 2 and the propeller 6 is mounted at the rear of the skeleton frame, the various parts being preferably so disposed that the center 65 of resistance is in substantially the same horizontal line as the center of screw thrust, and the center of buoyancy in substantially the same vertical line with the center of 70 gravity. 75

Projecting laterally from opposite sides of the skeleton frame or body 2 and hinged thereto at 7 are the wings of the sustaining planes 8. These sustaining planes may be 80 constructed in any suitable manner and may be held either in alinement with each other or at any desired dihedral angle by any suitable means such as the wires 9 which lead from the wings to the main frame.

Projecting forwardly from the main 85 frame of the aeroplane is an upper arm 10 and a lower arm 11 and these arms are disposed in the central vertical plane of the machine. The extremity of the upper arm 10 is provided with a sleeve or guide member 12 loosely receiving a longitudinal rod 13, the rear end of which is connected to a lever 14 arranged adjacent the seat 5 of the operator. Any suitable means, such as a pawl and ratchet, may be utilized for locking the lever 14 against movement, and a vertical plane or rudder 15 is pivotally mounted between the forward end of the connecting rod 13 and the forward end of 90 the lower arm 11 so as to turn freely about a vertical axis and serve as a means for guiding the machine either to the right or to the left. Intersecting this vertical plane 15 and arranged at substantially right angles thereto is a stabilizing plane 16, the outer edges of the said planes being connected by the wires or tie members 17 which serve to hold the planes rigidly in their 95 proper relative position. Through the medium of the lever 14 the rod 13 can be 100 105 110

shifted longitudinally so as to cause the stabilizing plane 16 to assume any desired angle with respect to the main sustaining planes 8, thereby compensating for the consumption of fuel for the engine and the consequent decrease in weight at that portion of the machine where the said fuel may be stored. The rear portion of the stabilizing plane 16 projects beyond the vertical plane 15 or rudder 15 and is designed to be flexed up and down for the purpose of causing the machine to ascend or descend. This stabilizing plane may be constructed in any suitable manner, and as shown in the present instance, it comprises a closed frame 16^a having a U shaped frame member 16^b pivotally connected to the rear portion thereof so as to swing freely up and down, both the closed frame 16^a and the U shaped frame member 16^b having the fabric 16^c applied thereto.

Secured to the rear edge of the flexible part of the stabilizing plane 16 is an endless cable 18, one section of the endless cable extending up and around a pulley or guide member 19 upon the vertical plane 15 and then down through the inside of the vertical plane and around one roller of a twin pulley 20 arranged adjacent the pivotal connection between the vertical plane and the lower arm 11, the said section of the endless cable extending rearwardly from the twin pulley 20 and being connected to the lower end of a main operating lever 21, while the opposite section of the endless cable extends downwardly from the stabilizing plane 16, around the opposite roller of the twin pulley 20, rearwardly to a pulley 22 connected to the mast 1 by a spring 23, and thence forwardly to the lower end of the main operating lever 21. It will thus be obvious that as the lower end of the main lever 21 is moved either toward the front or rear of the machine the endless cable 18 will operate to flex the rear portion of the stabilizing plane 16, any slack within the said endless cable being taken up by the spring 23, and struts 24 projecting both above and below the equalizing plane engage the endless cable so as to enable the movements of the cable to operate readily to produce the desired flexing of the stabilizing frame without any binding action.

The main operating lever 21 is mounted at an intermediate point in its length upon a universal joint and while this may be accomplished in any desired manner, the lever is shown in the present instance as pivoted upon a transverse bolt 25 carried by a ring 26 arranged at an intermediate point in the length by a wire 27. A sleeve 28 is slipped upon the upper end of the lever 21 so as to rotate freely thereon and is provided at its upper end with a wheel 29 which is designed to be grasped by the operator. The lower

end of the sleeve 28 is connected by the bevelled gearing 30 to a drum 31 mounted upon the lever so as to turn about an axis at right angles thereto. Wound upon this drum 31 is a cable 32 the ends of which extend downwardly and pass around pulleys or guide members 33 applied to the ring 36. From these pulleys 33 the ends of the cable extend forwardly where they are connected to the tie wires 17 upon opposite sides of the vertical plane 15 and also to the forward edge of the said vertical plane. With this construction, it will thus be obvious that by turning the wheel 29 the cable 32 can be controlled in such a manner as to turn the vertical plane 15 and guide the machine either to the right or to the left.

The invention also contemplates means for producing lateral equilibrium, and for this purpose an auxiliary plane 34 is mounted upon the outer end of each of the sustaining planes 8, the said auxiliary planes each normally assuming a vertical position parallel to the line of flight, and being mounted to turn about an axis parallel to the main plane and inclined to the line of flight so as to have after a revolution of 90 degrees an angle to the sustaining plane. Each of these auxiliary planes 34 is shown as pivotally mounted between the two limbs of a U shaped member 35 rigidly applied to and carried by the tip of the main plane 8, the base of the said U shaped frame 35 extending below the main sustaining plane 8 and being covered with a fabric as indicated at 36 so as to provide a downwardly projecting wing for producing what is termed the "end slip." The upwardly projecting limbs of the U shaped frame 35 are arranged in a vertical plane which is disposed parallel to the line of flight, and in the construction illustrated on the drawings, the forward limb is provided at its upper end with an inwardly projecting lateral arm 35^a, the rear edge of the auxiliary plane 34 being pivoted directly to the rear limb of the member 35, while the forward edge of the auxiliary plane is provided with a laterally projecting arm 37 which is pivoted to the end of the before mentioned arm 35^a of the forward limb. This lateral arm 37 is of such a length that when the auxiliary plane 34 is in a vertical position, as indicated in full lines in Figs. 2 and 3, it is parallel to the line of flight and in the same plane as the U shaped member 35 so as not to influence the motion of the machine. However, when the auxiliary plane is swung upwardly into a substantially horizontal position it is disposed at an angle to the main sustaining plane 8 and tends to lift that side of the machine. This is due to the fact that the arm 35^a which was previously horizontally disposed is now vertically disposed and hence elevates the forward end of the auxiliary plane with respect to 130

the main sustaining plane and the rear end of the auxiliary plane. Assuming the auxiliary planes 34 to be swung into a vertical position, the lower edges thereof are connected to flexible members 38 which pass around the guide members or pulleys 39 and are secured to coil springs 40 which are preferably arranged between the upper and lower fabric coverings of the main sustaining planes, although they may be mounted in any desired manner, the tension of the said springs normally serving to hold the auxiliary planes in a vertical position. The upper edges of the auxiliary planes are connected to the wires or cables 41 which pass around the pulleys or guide members 42 and through the main sustaining planes 8 at substantially the middle portions thereof, the ends of the said wires being secured to the main lever 21. It will thus be obvious that by swinging the main operating lever 21 laterally either one of the auxiliary planes 34 may be swung upwardly into an operative position for lifting that side of the machine to produce equilibrium, the opposite auxiliary plane remaining stationary, that by swinging the main lever 21 to the front or rear the rear edge of the stabilizing plane 16 can be flexed for causing the machine to ascend or descend, and that by turning the wheel 29 and causing the sleeve 28 to rotate upon the upper end of the operating lever the vertical plane 15 may be turned so as to guide the machine either to the right or to the left.

A wheel 43 is carried by the lower arm 11 of the frame at an intermediate point in the length thereof, while a second wheel 44 is journaled upon two pivotally connected levers 45 and 46 at the junction thereof, the lever 45 having the free end thereof pivoted to the lower end of the mast 1 while the lever 46 has the free end thereof pivotally connected to a slide 47 mounted upon a vertical rod or guide 48 which has the upper end thereof secured to the seat 5 while the lower end is received within a slot in the upper portion of the mast 1 and secured to the mast at the base of the said slot. A coil spring 49 surrounds this vertical rod 48 and bears yieldingly against the slide 47. The two wheels 43 and 44 are brought into use in the usual manner when the machine is on the ground, and the peculiar manner of mounting the rear wheel 44 serves to absorb all sudden shocks and prevent injury to the machine when alighting at the end of a flight. The two wheels 43 and 44 are preferably covered with a fabric so as to reduce the resistance thereof to the air when the machine is in flight.

Having thus described the invention, what I claim as new and desire to secure by Letters Patent is:

65 1. An aeroplane provided with a verti-

cally arranged rudder and a horizontally arranged stabilizing plane intersecting the rudder and formed with a flexible portion, means for turning the rudder about a vertical axis to guide the aeroplane laterally, 70 means for swinging the rudder about a horizontal axis to vary the angle of the stabilizing plane, and means for flexing the stabilizing plane for causing the aeroplane to ascend or descend. 75

2. An aeroplane provided with a rudder and a stabilizing plane intersecting the rudder and rigid therewith, a portion of the said stabilizing plane projecting beyond the rudder and being flexible, means for turning the 80 rudder about a vertical axis to guide the aeroplane laterally, means for swinging the rudder about a horizontal axis to vary the angle of the stabilizing plane, and means for flexing the projecting portion of the 85 stabilizing plane for causing the aeroplane to ascend or descend.

3. In an aeroplane, the combination of a main frame, sustaining planes carried by the main frame, a pair of spaced arms projecting from the main frame and arranged in a vertical plane, a guide member upon one of the arms, a rod slidably mounted within the guide member, a rudder pivotally mounted between the said rod and the opposite arm, 90 means for turning the rudder about its axis, and a stabilizing plane carried by the rudder, the angle of the stabilizing plane being adjusted by sliding the before mentioned rod. 100

4. In an aeroplane, the combination of a main frame, sustaining planes carried by the main frame, a pair of spaced arms projecting from the main frame and arranged in a substantially vertical plane, a guide member at the end of one of the arms, a rod slidably mounted within the guide member, a rudder pivotally mounted between the end of the rod and the opposite arm, means for turning the rudder about its axis, a stabilizing plane carried by the rudder and formed with a flexible portion, the angle of the stabilizing plane being varied by sliding the before mentioned rod, and means for flexing the stabilizing plane. 110

5. An aeroplane provided with a rudder, a stabilizing plane carried by the rudder and formed with a flexible portion, a lever, means actuated by the swinging of the lever for flexing the stabilizing plane, a sleeve 120 loosely mounted upon the lever, and means actuated by the sleeve for turning the rudder.

6. An aeroplane provided with a rudder and a stabilizing plane carried by the rudder, a portion of the stabilizing plane being flexible, a lever mounted upon the aeroplane, means co-operating with the lever to flex the stabilizing plane, a drum mounted upon the lever, means upon the lever for controlling 130

- the drum, and a cable wound upon the drum and having an operative connection with the rudder.
7. An aeroplane provided with a rudder and a stabilizing plane carried by the rudder, a portion of the stabilizing plane being flexible, a lever mounted upon the aeroplane, means coöperating with the lever to flex the stabilizing plane, a sleeve loosely mounted upon the lever, a drum mounted upon the lever and geared to the sleeve, and a cable wound upon the drum and having an operative connection with the rudder.
8. An aeroplane provided with a rudder, a lever pivotally mounted upon the aeroplane, a sleeve slipped over one end of the lever so as to rotate freely thereon, a drum carried by the lever and geared to the sleeve, and a cable wound upon the drum and having an operative connection with the rudder.
9. An aeroplane provided with a rudder, a lever pivotally mounted upon the aeroplane, a sleeve rotatably mounted upon the lever, a drum carried by the lever and geared to the sleeve, guide members adjacent the pivot point of the lever, and a cable wound upon the drum and passing around the said guide members and having an operative connection with the rudder.
10. In an aeroplane, the combination of a main frame, sustaining planes carried by the main frame, a pair of arms projecting from the main frame, a guide member upon one of the arms, a rod slidably mounted within the guide member, a rudder pivotally mounted between the rod and the opposite arm, a stabilizing plane intersecting the rudder and rigid therewith, a lever pivotally mounted upon the main frame, means coöperating with the lever to turn the rudder about its axis, and means for sliding the before mentioned rod within the guide member for adjusting the angle of the stabilizing plane with respect to the sustaining planes.
11. In an aeroplane, the combination of a main frame, sustaining planes carried by the main frame, and auxiliary balancing planes mounted to turn about an axis inclined to the line of flight and parallel to the sustaining planes so that they are inoperative when in a vertical position but have a lifting power when swung into a substantially horizontal position.
12. In an aeroplane, the combination of a main frame, sustaining planes carried by the main frame, a pair of limbs projecting from each of the sustaining planes, and an auxiliary balancing plane pivotally mounted between each pair of the limbs, one end of the balancing plane being pivoted directly to one of the limbs while the opposite end is provided with a lateral arm which is pivoted to the other limb, the said lateral arm causing the auxiliary plane to assume an inoperative position parallel to the line of flight when swung into a vertical plane, but to have a lifting power when turned into a substantially horizontal plane.
13. In an aeroplane, the combination of a main frame, a sustaining plane carried by the main frame, a U shaped frame at the end of the sustaining plane, the base of the said U shaped frame extending below the sustaining plane while the limbs thereof project above the sustaining plane, means coöperating with the said downwardly projecting base of the U shaped frame to prevent end slip, and an auxiliary balancing plane pivoted between the upwardly projecting limbs of the U shaped frame.
14. In an aeroplane, the combination of a main frame, sustaining planes carried by the main frame, a rudder, a stabilizing plane having a portion thereof flexible, an auxiliary balancing plane, a lever mounted upon the main frame to turn about a universal joint, an operative connection between the lever and the balancing plane whereby the latter is operated when the lever is swung in one direction, an operative connection between the lever and the stabilizing plane for flexing the latter when the lever is swung in a direction at right angles to its previous direction of movement, and means upon the lever for controlling the rudder.
15. In an aeroplane, the combination of a main frame, sustaining planes carried by the main frame, a pair of arms projecting from the main frame, a guide member upon one of the arms, a rod slidably mounted within the guide member, a rudder pivotally mounted between the rod and the opposite arm so as to turn about a substantially vertical axis, a stabilizing plane intersecting the rudder and rigid therewith, a portion of the stabilizing plane being flexible, auxiliary balancing planes upon the sustaining planes, a lever mounted upon the main frame to turn about a universal joint, an operative connection between the lever and the auxiliary planes for operating the latter when the lever is swung in one direction, an operative connection between the lever and the stabilizing plane for flexing the latter when the lever is swung in a direction at right angles to its previous movement, and means upon the lever for controlling the rudder.

In testimony whereof I hereby affix my signature in presence of two witnesses.

AUGUST R. LASSEL.
